M. B. H., OF COLOGNE-HOLWEIDE, GERMANY

ROTARY ENGINE AND PUMP

Application filed May 26, 1927, Serial No. 194,460, and in Germany July 3, 1926.

This invention relates to the class of engine having a group of circumferentially arranged cylinders and a group of appertaining pistons, one of said groups rotating continuously and 5 the other intermittently, being alternately relatively held back and accelerated forward. Such engines unite in themselves all the advantages of rotary engines, in particular that of direct transmission of the power to or from 10 a rotating power shaft, with the advantages of the usual cylinder and crank shaft engine. The basic class or type is usable not only for power engines but also for working machines which are inversions of power engines, for 15 example pumps and compressors.

The essential conditions for practical operation of such a machine are the following: The working force must be transmitted in tangential direction, directly to the driving shaft. The movement of the intermittently rotating group, for example the pistons must be so controlled that the pistons alternately during one stroke remain stationary and during the next stroke move through 2a, 20 if a is the distance moved through during one stroke, i. e. half the piston movement, by the uniformly rotating cylinders. The mechanism which controls the piston movement must not take part in the transmission of power, since otherwise purely tangential transmission of the power is not possible. The pistons during their stationary period, that is during the power stroke, must be locked against movement in either direction. 25 This locking must be absolute, that is it must be derived from the stationary part of the machine. Locking of the pistons in relation to the cylinders as hitherto proposed is naturally insufficient, since then during the power 30 stroke the force acts on the pistons to drive them back just as much as on the cylinders to drive them forward. The pistons in their movement must be accelerated or retarded in a continuous manner. The movement must 35 not start suddenly from rest or stop suddenly. In practically all hitherto known constructions of such motors the piston movement commences suddenly from rest with the full speed of the cylinders, or ends suddenly therewith. Practically however there is no mate-

rial which will stand the shocks of such action. The movement of the pistons must be controllable to follow closely some speed curve known to be the optimum.

The present invention has for its object a 55 machine satisfying all the essential conditions and consists in the combinations described below and pointed out in the claims.

In this motor the piston movement positively follows a speed curve known to be the 60 optimum; it is not however bound to one particular curve, but can be arranged to follow any suitable curve. The pistons during their stationary period are locked against 65 both directions of rotation, and not just relatively to the cylinders but absolutely to the stationary part of the machine.

An internal combustion engine in accordance with the invention is illustrated by way 70 of example in the accompanying drawings.

The upper half of Figure 1 is a section on the line I—I of Figure 2. The lower half of Figure 1 is an elevation on the line Ia—Ia of Figure 2.

The upper half of Figure 2 is a section on the line II—II—II—II of Figure 1. The lower half of Figure 2 is a section on the line II—IIa of Figure 1.

Figure 3 is a section on the line III—III of Figure 9.

Figure 4 is a section on the line IV—IV of Figure 9.

Figure 5 is a speed diagram.

Figure 6 is a diagram showing the path of the pin 13.

Figure 7 shows an alternative connecting arrangement.

Figure 8 shows another alternative connecting arrangement and

Figures 9 and 10 are respectively front 90 views and sectional plan on line X—X of Figure 9 of the head end of the connecting rod shown in Figure 1, shown on an enlarged scale.

In Figure 5 of the accompanying drawings 95 the piston velocity is illustrated in graph form. The interval $2s$ represents the path of the pistons between the commencement of the first and second movement cycle and so forth. The half value of this interval is then s and

may be termed the stroke of the machine, analogous to the stroke in an ordinary crank motor. During all strokes s the cylinders rotate with substantially uniform speed v . The 5 piston speed must then be 0 during the first stroke, while in the second stroke the speed must proceed from 0 through a maximum to 0 again. The course of this speed curve is so regulated that the piston during the period 10 the cylinder traverses one stroke s covers the full interval $2s$. In other words, after a full motion cycle the pistons will again occupy the same positions relative to the cylinders. In this way smooth operation of the 15 machine is achieved and furthermore it is technically possible to construct the machine from the point of view of materials. All other constructions of the same basic idea fail on the question of materials. In order 20 now to enable the expansion energy in the cylinder to be used tangentially, there must not be any power transmitting connection between the pistons and cylinders during the working stroke. The back pressure on the 25 pistons must therefore be taken by the stationary part of the machine. A lock must therefore be provided between the pistons and stationary part of the machine, which on one hand prevents rotation of the pistons in the 30 opposite direction to the cylinders during the power stroke, and on the other hand does not allow the pistons to move in the direction of the cylinders under the action of the vacuum during the suction stroke. In other words, 35 the locking must act in both directions of rotation. Advantageously the pistons are always locked against rotation opposite to the rotation of the engine and in addition during every alternate stroke against rotation in the 40 same direction as the engine.

In the stationary part 3 of the engine is borne a shaft 4, on which a disc 1 to which the cylinders are rigidly connected, is keyed. Instead of the two cylinders shown, any desired 45 number can be used.

A piston carrier 2 to which the pistons are rigidly connected is rotatably borne in relation to the cylinder disc 1. The cylinder disc 1 carries on one end of its hub a cam 7 concentric with which is a cam 8 on the piston carrier 2. On the cam surfaces 7 and 8 slide the two ends of a lock lever 6, which is pivoted at the centre on a bolt 5 secured to the stationary part 3 of the engine. The cam 50 curve 7 comprises a recessed part 7b and a raised part 7a concentric with the axis of the machine, for each double stroke, while the cam curve 8 comprises a long tooth for each pair of parts 7b and 7a on the curve 7. When 55 the part 7a of the cam curve 7 is sliding on the end of the lever 6, the other end of the lever clearly locks the tooth of the curve 8 against counter-clockwise rotation. It also 60 locks the curve against rotation in the clockwise direction since owing to the increasing 65

height of the tooth 8 towards the right, if such rotation were to commence it would again tend to turn the lever 6 counter-clockwise which is prevented by the contact of the lever 6 with the raised part 7a. In other 70 words, as long as the raised part of the curve 7 operates, the pistons are locked against both directions of rotation. Considering Figure 1 during the stationary period of the piston group, the upper end of the lever 6 runs on the circular portion 7a of the curve 7, this period just having commenced in Figure 1. During the previous stroke interval the curve 7 has moved through an angle a and the curve 8 through an angle $2a$. The hollow part 7b of the curve 7 is shaped so that the ends of the lever contact with both curves when both curves are moving. The curve 7 runs steadily and continuously while the curve 8 runs intermittently as explained above, under the 80 action of a suitable mechanism described in detail below. Considering now the forces which act in the position shown in Figure 1 and during the succeeding stroke when the curve 8 must be locked in both directions. If 85 the curve 8 tends to move in the direction of rotation of the engine, i. e. counter-clockwise, the lever tends to rotate counter-clockwise on its pivot 5, which is resisted by the circular part of the curve 7 and the pivot 5. Consequently the curve 8 cannot move in counter-clockwise direction. If the curve tends to move in the opposite direction to the engine, i. e. clockwise, as occurs during the suction stroke, this will be resisted by jamming of the 90 curve 8 against the end of the lever, since the curve 8 slopes in toward the centre, and therefore such motion cannot take place as long as the materials hold. The motion is further resisted by friction which in itself is slight, 95 but which tends to rotate the lever 6 clockwise which increases the jamming action. When both curves are moving, forces in a direction counter to the rotation of the engine do not normally occur, owing to the action of 100 the mechanism connecting the piston and cylinder groups. If such a force did arise it would be resisted just as in the position shown in Figure 1 by the inward slope of the curve 8 and the tendency to turn the lever 6 105 clockwise by the friction on the lever. During the stationary period of the pistons the operating mechanism between the pistons and cylinders, as shown below, is out of action. It is clear therefore that all the forces acting 110 on the piston are taken by the fixed part 3 of the engine. As can be seen from the speed diagram, Figure 5, the lock lever 6 does not serve to brake the speed of the pistons, since at the instant in question the pistons have no 115 speed. The purpose of the lock lever 6 is solely the locking of the stationary pistons against both directions of rotation. Only when the lock lever 6 reaches the recessed 120 parts of the curve 7 is the locking by the 125

curve 8 against rotation in the same direction as the engine released, and the pistons can then move according to the speed curve of Figure 5 under the actuation of the mechanism between the cylinders and pistons.

The epicycloid gear shown as an example, of which the connecting rod length is positively variable, is used as a mechanism satisfying the aforementioned conditions. The 10 connecting rod pin 13 connected with the cylinder disc describes the curve shown in Figure 6. This path consists of two portions of equal time length, the arcs 29 to 33 and the loops 29-30-29 (or 33-34-33). During 15 the description of the loops the pistons must remain stationary and, as above described, locked to the stationary part of the engine. During the section 29-33 of the path, the pistons are driven by the mechanism 20 in the same direction as the cylinders, with an average speed which is twice that of the cylinders. It can be seen that the requirement that the pistons remain stationary cannot be fulfilled without further provision 25 since the path proceeds backwards and forwards over a short distance and does not in itself represent a stationary period. It is therefore necessary to provide a device which compensates for the movements in question. 30 The action of the device illustrated by way of example is explained as follows:

On the stationary part 3 of the machine is a toothed crown 9 on which rolls a pinion 10. This pinion is fast on the spindle 11 of a 35 crank shaft borne by the cylinder disc 1. By means of a web 12 the rotation of the pinion 10 is transmitted to the pin 13 which then describes the path shown in Figure 6. The piston body 2 carries a pin 20. These two 40 pins 13 and 20 are coupled by a connecting rod 14 of which one end is borne on the pin 13, and of which the other end carries the compensating device for varying its length. For this purpose the other end of the connecting rod 14 surrounds the pin 20 frame 45 fashion. In the opening 17 of this frame a small cross head 19 which surrounds the pin 20, can slide in either direction. Over the frame form opening 17 extend two bars 50 15 secured to or formed integral with the rod 14'. In the centre of these bars 15 is borne on a pin 21 a toothed wheel 18^a provided with a lever arm 18. To the left and right of the cross head 19, within the frame 17 and borne 55 between the bars 15 are two eccentrics 16, to which toothed wheels 22 are secured. The two toothed wheels 22 mesh with the toothed wheel 18^a. The free end of the lever 18 on the wheel 18^a is articulated to a rod 23 which 60 is guided in the rotatable guide 24 mounted upon the piston body 2. The free end 27 of the rod 23 operates in a cam groove 26. This curve 26 is cut in a projection 25 secured or formed upon the rod 14. The curve 26 is so 65 formed that the rod 14 has its normal length

when the point 13 is describing the parts 31-32 of the path in Figure 6, the cross head 19 being so controlled by the eccentrics 16 however, that the changes in length necessitated by the passage over the loops are al-

70

ways produced. The changes in length of the connecting rod already begin at 28 (or 32) and end at 31 (or 35). While immobilization of the point 20 is produced in this way, during the sections 28-29; 29-31; 75 32-33; 33-35; the speed is respectively reduced to 0 or raised from 0.

Another simple arrangement for controlling the piston movement is shown by way of example in Figure 7 of the accompanying 80 drawings. The pistons 40 are moved forward by a rod 41 which is pivoted to the pistons at 42. The end point 43 of this rod moves (1) by sliding on the crank arm 44, the movement of which is derived in any 85 suitable way from the movement of the engine, (2) on the curved path 45 which is rigid with the cylinders and is so formed that the pistons receive exactly the above described movement.

90

Another arrangement of the mechanism for controlling the piston movement is diagrammatically shown in Figure 8 of the accompanying drawings. The point 42 on the pistons is guided in the curve 45 which rotates rigidly with the toothed wheel 48, the prescribed motion being produced by suitably forming the curve 45. With this arrangement, by suitably forming the curve, the speed curve can be given any desired 95 form, for example it can be made parabolic or the like. The comparatively large curve is formed in a disc 47, which can at the same time serve as a flywheel.

100

What I claim is:—
1. In a machine of the class described, means for locking the intermittently rotating group both ways during its stationary period to the stationary part of the machine, and positively controlled mechanism separate from the mechanism transmitting the power forces connecting the two groups adapted to hold said intermittently rotating group still during its stationary period and to forward said intermittently rotating group with a mean speed of twice the machine speed without shocks at the commencement and finish during the moving periods of said group.

105

2. In a machine of the class described, means for locking the intermittently rotating group both ways during its stationary period to the stationary part of the machine, mechanism operated by the continuously rotating group including a pin describing an epicycloidal path, a coupling rod connecting said pin and said intermittently rotating group, and positively controlled means for automatically varying the length of said rod 110 so that said intermittently moving group is 120

125

130

held still and forwarded without shock at the appropriate times.

3. In a machine of the class described, means for locking the intermittently rotating group during its stationary period to the stationary part of the machine, mechanism operated by the continuously rotating group including a pin describing an epicycloidal path, a coupling rod pivoted at one end to said pin, a cross head sliding in the other end of said rod pivoted to said intermittently rotating group, and cam means for automatically sliding said cross head so that said intermittently moving group is held still and forwarded without shock at the appropriate times.

4. In a machine of the class described, means for locking the intermittently rotating group during its stationary period to the stationary part of the machine, mechanism operated by the continuously rotating group including a pin describing an epicycloidal path, a coupling rod pivoted at one end to said pin, a cross head sliding in the other end of said rod pivoted to said intermittently rotating group, an eccentric borne in said rod on each side of and contacting with said cross head, means including an arm for rotating said eccentrics, a cam borne on said rod and a connecting member pivotally and slidably borne on said intermittently rotating group coupled to said arm and operatively connected with said cam.

5. In a machine of the class described, a concentric cam path on the continuously rotating group, a second concentric cam path on the intermittently rotating group, a lock member pivoted to the stationary part of the machine co-acting with said cam paths to lock said intermittently rotating group both ways to said stationary part of the machine during its stationary periods and positively controlled mechanism separate from the mechanism transmitting the power forces connecting the two groups adapted to hold said intermittently rotating group still during its stationary period and to forward said intermittently rotating group with a mean speed of twice the machine speed without shocks at the commencement and finish during the moving periods of said group.

6. In a machine of the class described, a concentric cam path on the continuously rotating group, a second concentric cam path on the intermittently rotating group, a lock member pivoted to the stationary part of the machine co-acting with said cam paths to lock said intermittently rotating group to said stationary part of the machine during its stationary periods against rotation in either direction and against rearward rotation during its moving periods, and positively controlled mechanism separate from the mechanism transmitting the power forces connecting the two groups adapted to hold said in-

termittently rotating group still during its stationary period and to forward said intermittently rotating group with a mean speed of twice the machine speed without shocks at the commencement and finish during the moving periods of said group.

7. In a machine of the class described, a concentric cam path on the continuously rotating group, a second concentric cam path on the intermittently rotating group, a lock member pivoted to the stationary path of the machine co-acting with said cam paths to lock said intermittently rotating group to said stationary part of the machine during its stationary periods against rotation in either direction and against rearward rotation during its moving periods, mechanism operated by said continuously rotating group including a pin describing an epicycloidal path, a coupling rod connecting said pin and said intermittently rotating groups, and positively controlled means for automatically varying the length of said rod so that said intermittently moving group is held still and forwarded without shock at the appropriate times.

8. In a machine of the class described, a concentric cam path on the continuously rotating group, a second concentric cam path on the intermittently rotating group, a lock member pivoted to the stationary path of the machine co-acting with said cam paths to lock said intermittently rotating group to said stationary part of the machine during its stationary periods against rotation in either direction and against rearward rotation during its moving periods, a toothed crown on said stationary part, a pinion borne by said continuously rotating group meshing with said crown, a crank pin rotated by said pinion, a coupling rod connecting said pin and said intermittently rotating groups, and positively controlled means for automatically varying the length of said rod so that said intermittently moving group is held still and forwarded without shock at the appropriate times.

In testimony whereof I have signed my name to this specification.
